EYELASH CURLER

Abraham Resnikoff and Irving Bernstein,
Brooklyn, N. Y.

Application February 8, 1945, Serial No. 576,749

4 Claims. (Cl. 132—32)

1

This invention relates to an improved eyelash curler, and one of its objects is to provide a lever with an arched upper jaw fixed thereon and parallel guides, a movable jaw which engages the parallel guides and is held thereby to parallel motion toward and away from the fixed jaw, and a second lever which is pivoted on the first lever, but which is provided with a cam arranged to shift the movable jaw toward and away from the fixed jaw, so that the movable jaw is not rocked against the fixed jaw and bruising or shearing of the engaged eyelash hairs is thereby avoided.

Another object of the invention is to provide a yielding eyelash engaging jaw face of resilient rubber or other similar material, which is moulded or vulcanized upon the movable jaw, so as to completely enclose the material of which the frame of the movable jaw is made.

Another object of the invention is to provide a new and improved eyelash curling device having a movable jaw frame member which can be removed from the device to renew or replace the resilient rubber jaw face member when the latter becomes worn.

Still another object of the invention is to provide a new and improved eyelash curling device which is simple and easy to operate and which is safe to use.

With the above and other objects in view, the invention relates to certain new and useful constructions, combinations, and arrangements of parts, clearly described in the following specification, and fully illustrated in the accompanying drawings, in which:

Fig. 1 is a front elevation.

Fig. 2 is a vertical sectional view, taken on line 2—2 of Fig. 1, looking in the direction of the arrows, showing the movable jaw in its lower position.

Fig. 3 is a similar view, showing the movable jaw in its upper position.

Fig. 4 is a transverse sectional view, taken on line 4—4 of Fig. 3, looking in the direction of the arrows.

Referring to the accompanying drawings, which illustrate a practical embodiment of the invention, 5 designates a lever which is provided with a doubled shank 6, the lower ends of which are looped upon said shank to provide the doubled finger hold loop 7. The upper end of lever 5 is formed with outwardly extending diagonal bars or arms 8 and 9, which terminate in parallel vertical guides 8A and 9A, each of which is formed with a longitudinal groove 10. Said guides 8A and 9A are channel-shaped in cross-section.

To the upper ends of the grooved guides 8A and 9A, an arched upper jaw 11 is fixed, as by welding. This upper jaw is formed with an arched lower eyelash curling edge 11A.

2

The lever 5 is equipped with a bearing ear or lug 12, which may be formed of sheet metal folded on the shank 6, and this bearing ear or lug is engaged by a similar bearing ear or lug 13, secured to the second doubled lever 14, and a rivet 15 pivotally connects the two bearing ears or lugs 12 and 13 to each other, so that the lever 14 can have free pivotal movement on the lever 5. The lower end of the lever 14 is formed with a doubled loop 16, which forms a finger hold for the same, and the upper end or terminal of said lever 14 is formed with another doubled loop 17, disposed on the opposite side of the shank 14' of said lever 14 to the finger hold loop 16. The loop 17 includes a doubled arm 17A, which is disposed in a diagonal direction on the upper end of the shank 14', and which is slightly curved so as to have a cam-like form or shape.

The movable jaw or frame 18 is arranged to slide in the guides 8A and 9A of the lever 5, and this movable jaw includes the vertical side bars 18A and 18b, which directly engages the grooves 10 of these guides, the arched upper bar 18C, and the lower bar 18D. The lower and movable jaw 18 is formed of springy round wire stock, so that the side bars 18A and 18b will have a smooth sliding action in the grooves 10, and the arched upper bar 18C and the lower bar 18D are integral with the side bars 18A and 18b.

The lower jaw 18 is permanently held against rocking in the grooved side bars 8A and 9A of the lever 5, by the parallel side bars 18A and 18b, which provide considerable parallel bearing in the grooves 10 of the side arms 8A and 9A. The upper arched bar 18C of the movable jaw 18 is provided with a resilient rubber jaw face 19, which completely encloses said arched bar 18C, and which is moulded or vulcanized thereon, and which is formed with a hair engaging integral forming ridge or projection 19A, adapted to have contacting engagement with the eyelash curling edge 11A. The forming ridge 19A is somewhat wider than the edge 11A, and the latter is adapted to engage ridge 19A midway of its sides, so that the eyelash hairs disposed between the edge 11A and the resilient ridge 19A will be bent, and can thereby be curled, by clamping the two jaws upon the eyelash hairs.

The lower jaw 18 is engaged by the slightly curved cam arm 17A of the lever 14, and a wire yoke 20 loosely couples said cam arm 17A to the lower cross bar 18D of said movable lower jaw 18, this yoke 20 being formed with terminal eyes 20A and 20B, which encircle the cross bar 18D, and slidably couple the cam arm 17A to the movable jaw 18.

When the lever 14 is moved so that the lower end of the same will approach the lower end of the lever 5, the cam arm 17A of the lever 14 will slide or ride against the cross bar 18D of the

movable jaw 18, and force the resilient ridge 19A toward the curling edge 11A of the upper fixed jaw. When the lower end of the lever 14 is moved away from the lower end of the lever 5, the cam arm 17A of said lever 14 will slide against the yoke 20, thereby moving the movable or lower jaw 18 away from the fixed or upper jaw 11.

Due to the fact that the lever 14 does not have any direct or indirect pivotal connection with the movable jaw 18, the latter is not rocked across the curling edge of the fixed upper jaw 11, when said movable jaw 18 is forced against eyelash hairs placed between the two jaws, when the two jaws are pressed together to curl the eyelash hairs, or when pressure is released to move the said jaw apart.

As a result of this arrangement the danger of bruising the eyelash hairs, or of partly or wholly shearing them, as a result of the rocking of the movable jaw 18 on the frame of the fixed jaw 11, is eliminated.

When the movable jaw 18 is first released from the pressure placed upon it, the cam arm 17A will have a slight lost motion on said movable jaw, which will aid in the gradual release of the engaged eyelash hairs from the curling pressure placed upon them, and tend to prevent a sudden pull upon these hairs, during the separating action of the two jaws, due to the temporary adhesion of the hairs to the rubber.

Moreover, the amount of pressure applied and the rate at which the pressure is applied upon the eyelash hairs, can be modified by the angle and length of the cam arm 17A or by the curvature of it.

It is noted that the bearing ears or lugs 12 and 13 of the levers 5 and 14 pivotally connect said levers to each other in side-by-side relation, and that this avoids the shearing relation between the two levers, which is in current use, and which results in frequent pinching of interfering hair strands or portions of the flesh of the user.

This side-by-side pivotal mounting provides normally open clearances or gaps between the levers at the points of pivotal movement, and only the cam arm 17A projects over the opposite lever 5, and this arm is disposed at an angle of almost ninety degrees, at the point it crosses the opposite lever 5, or moves between the guides 8 and 9, and at this point is spaced laterally and inwardly from these guides, so as to avoid any shearing relation between related parts. At the point of contacting or sliding engagement with the lower cross bar of the frame loop which forms the movable lower jaw 18, the engagement is at right angles to the lower cross bar.

One of the features of the invention is that the entire movable lower jaw frame member 18 can be removed as a single unit from the device whenever it is desired to replace or renew the resilient rubber jaw face member 19 when the latter becomes worn. This is accomplished by removing loop 17 of cam arm 17A from yoke 20. The entire movable lower jaw frame member 18, due to the springy material from which it is made, can then be snapped or forced out of guides 8A and 9A. The resilience or springiness of said guides 8A and 9A assist in the removal or

insertion of said jaw frame member from the frame of the fixed jaw member.

It is understood that various changes in the construction of the details shown, in their combination and arrangement, and in the choice of materials used, may be made, within the scope of the invention, as defined by the claims hereof.

Having described the invention, it is claimed:

1. An eyelash curler, consisting of a lever having parallel guides formed with opposing grooves, a fixed jaw on said lever outwardly of the guides, a movable jaw having side bars sliding in said opposing grooves and a top arched bar provided with a resilient hair engaging member, said movable jaw having a lower cross bar, a second lever pivoted to the first lever, said second lever having a cam arm slidably engaging said cross bar of the movable jaw, and a yoke coupling said cam arm to said cross bar, whereby the second lever will actuate the movable jaw toward and away from the fixed jaw.

2. An eyelash curler, consisting of a pair of levers pivotally connected to each other in side-by-side relation, one of said levers having a fixed jaw thereon and parallel guides adjacent said fixed jaw, a movable jaw slideable on said parallel guides, and a cam arm on the other lever arranged to slidably engage said movable jaw to move the same toward and away from the fixed jaw, a yoke coupling said cam arm to said movable jaw.

3. An eyelash curler, consisting of a lever having opposing guides and a fixed jaw mounted on the ends of the guides, a frame loop sliding on said guides and provided with an upper arched bar, a resilient rubber element enclosing said arched bar and provided with a ridge adapted to have contacting engagement with the fixed jaw, a second lever pivoted to the first lever, said second lever having a cam arm adapted to engage and slidably actuate the frame loop toward and away from the fixed jaw to move said ridge into contacting engagement with the fixed jaw and away from said contacting engagement.

4. An eyelash curler, consisting of a lever having a fixed jaw thereon, a movable jaw sliding on the lever, a second lever pivoted to the first-named lever, said first lever having a cam arm in slidable engagement with the movable jaw, to shift the movable jaw toward and away from the fixed jaw, a yoke coupling said cam arm to said movable jaw and a resilient sleeve enclosing the movable jaw and provided with a ridge to engage the fixed jaw.
